UNITED STATES PATENT OFFICE

2,007,543

VALVE SEAT INSERT

George Ernest Meeker, Utica, N. Y.

Application October 30, 1933, Serial No. 695,855

5 Claims. (Cl. 123—188)

My invention relates to a valve seat insert and I declare the following to be a full, clear, concise and exact description thereof sufficient to enable anyone skilled in the art to which it applies to make and use the same, reference being had to the accompanying drawing in which like figures refer to like parts throughout.

The object of the invention is to provide a valve seat that is held permanently in place by mechanical means so that there is no opportunity for it to work loose and as oftentimes happens fly off from its seat thereby accounting for a leaky valve and loss of compression in the cylinder of the engine.

15 Heretofore, due to the lack of means for holding the valve seat rigidly in predetermined position in the engine block, it would work loose under the terrific heat and pounding to which the actuation of the exhaust valve subjects it.

20 The object will be understood by referring to
the drawing in which,

Fig. 1 is a perspective view showing an engine block in fragment with the improved valve seat disposed therein, parts being in section.

25 Fig. 2 is a detail enlarged view showing a transverse section of the valve seat.

Fig. 3 is a detail enlarged view showing a section taken on the line 3—3 of Fig. 1.

Referring more particularly to the drawing, a fragment of an internal combustion engine block showing a valve port is illustrated at 1. Block 1 is counterbored at 2 for the reception of valve seat 3. Valve seat 3 is in the form of a ring whose outside diameter is determined by the counter bore 2 of the port of block 1. Valve seat or ring 3 is made of a hard steel to aid in resisting the terrific heat and pounding action of exhaust valve seat 3.

The means for holding valve seat or ring 3 rigidly in place within its counterbore 2 in block 1 embodies an annular flange 10 made integral with the lower edge 11 of ring 3. The lower edge of flange 10 is beveled at 8 with the apex outwardly for a purpose hereinafter described.

45 Furthermore, the diameter of the outer surface of flange 10 is reduced somewhat from the diameter of the outer surface of ring 3. This effects a slight shoulder at 15. The reduced diameter of flange 10 will allow it to slip down easily into counterbore 2 of block 1 and aid in guiding or steering ring 3 into correct position in counterbore 2. The outer diameter of ring 3 will fit snugly against the contiguous wall of counterbore 2 in block 1, whereby to prevent any leakage.

Flange 10 is reduced in thickness and is split at six places as at 16, whereby to allow flange 10 to curl outwardly when under pressure from above on ring 3. To this end an annular recess 18 is made in block 1 adjacent the lower outer edge of counterbore 2 and communicating therewith. Recess 18 provides an undercut housing in block 1, for the reception of flange 10 when forced therein by pressure on the upper edge of ring 3.

In operation, valve seat insert or ring 3 is disposed in counterbore 2 of block 1 with flange 10 downward. Said flange 10 will as mentioned above because of its slightly reduced outer diameter aid in guiding ring 3 into position in counterbore 2 of block 1. The lower edge 20 of flange 10 will come to rest on the horizontal surface 21 of block 1. A block not shown is then placed on top of ring 3 and struck with a hammer until flange 10 is forced outward and curled around into annular recess 18 ultimately assuming a substantially bead formation that is housed beneath the upper surface 22 of block 1. This latter disposition of flange 10 will hold permanently in position, exhaust valve seat 3, whereby to withstand the terrific heat and severe pounding action of said valve seat 3.

Furthermore, the bevel 8 on the lower edge of flange 10 will aid in directing said flange 10 towards and into annular recess 18 in block 1, whereas, the splits 16 in the sides of flange 10 will allow for outward expansion and curling of said flange 10 into annular recess 18.

It may be found desirable to make the upper portion of ring 3 of hard steel and to take the temper out of the lower or flange portion 10, to effect a more yielding metal in that location and thereby curl more easily when forced into recess 18. 35

It will be observed from the above structure that by forcing flange 10 into the annular recess 18, an annular bead is formed which partially underlies the material in block 1 whereby to hold said valve seat 3 rigidly in position and prevent its moving upwards as oftentimes occurred heretofore. 40

Moreover, heretofore one of the reasons for causing the valve seat 3 to work loose and fly off from its seat in block 1 was due to the cracking of said block 1. Under the present structure this would be impossible for the reason that ring 3 is not held in its seat in block 1 entirely by drive fit but also by the additional locking feature of flange 10 in recess 18.

Having thus described my invention what I claim as new and desire to secure by Letters Patent is as follows:

1. In a valve seat insert, an engine block having a counterbore therein, a ring member fitted into the counterbore in said block, another member formed integral with said first named ring member, a recess made in said block, means permitting said last named member to curl into said recess, whereby to hold said ring in said block.
2. In a valve seat insert, an engine block having a counterbore therein, a ring member fitted into the counterbore in said block, another member formed integral with said first named ring member, a recess made in said block, and slits formed in said second named member to permit the last named said member to curl in said recess, whereby to hold said ring in said block.
3. In a valve seat insert, an engine block having a counterbore therein, a ring member fitted into

the counterbore in said block, a flange formed integral with the first named ring member, an annular recess made in said block, said flange having slits formed therein allowing it to yield, whereby to curl into said recess and to hold said ring in said block.

4. In a valve seat insert, an under cut recess for a valve seat, a ring member having a flange formed thereon and slits formed in said flange to permit said flange to yield and curl under said valve seat in said recess, whereby to hold said ring in said valve seat.

5. In a valve seat insert, an under-cut recess for a valve seat, a ring member having a flange portion mounted thereon, an annular shoulder formed between said flange and said ring member and slits made in said flange to permit it to curl, under said valve seat, whereby to hold said ring in said valve seat.

G. ERNEST MEEKER. 20
